ABSTRACT

A furnace, adapted to produce molten metal in a melting chamber thereof, is pivotally mounted on a stationary support. A fume collector, having an opening formed therethrough to facilitate charging of the chamber, is fixedly mounted on the furnace. A generally annular collecting chamber is defined in the collector to circumvent such opening. The upper end of a first conduit is pivotally mounted on the collector and communicates with the collecting chamber whereas the lower end of the first conduit is mounted on the end of a stationary second conduit and communicates therewith to extract the fumes.

SHEET 2 OF 2

APPARATUS FOR COLLECTING AND EXTRACTING FURNACE FUMES

BACKGROUND OF THE INVENTION

Basic electric furnaces exude appreciable amounts of hot and noxious gaseous fumes, particularly during the charging and slag removing phases of a foundry operation. Various overhead hoods have been proposed to collect such gases for scavenging purposes. Examples of such hoods are disclosed in U.S. Pat. Nos. 3,372,523; 3,453,369; 3,482,827; and 3,539,692.

The hoods are normally moved aside from the stationary or pivotally mounted furnace during various phases of the foundry operation. Such movement thus prevents the hood from fully entrapping the fumes emanating from the furnace. In addition, the hoods are normally bulky and oftentimes tend to interfere with efficient operation of overhead cranes or like devices employed to charge the furnace.

SUMMARY OF THIS INVENTION

An object of this invention is to overcome the above, briefly described problems by providing an economical and non-complex apparatus for efficiently collecting and extracting fumes emanating from the melting chamber of a furnace. The chamber is defined in a vessel which is pivotally mounted on a support and a fume collector is mounted on the vessel. The collector has a generally annular collecting means defined therein to substantially circumvent an opening formed through the collector. A first conduit has one end pivotally mounted on the collector and a second end mounted on a stationary second conduit. Means are provided for permitting the vessel to pivot while simultaneously maintaining the first conduit's communication with the collector and the second conduit.

In the preferred embodiment of this invention, a cover is movably mounted on the collector to selectively cover the opening formed therethrough. In addition, the collector may comprise a pair of vertically spaced plates having annular portions detachably mounted thereon and defining the collector's opening. Circumferentially disposed flow guide means are attached between the annular portions.

BRIEF DESCRIPTION OF THE DRAWINGS

Other objects of this invention will become apparent from the following description and accompanying drawings wherein:

FIG. 1 is an isometric view illustrating an apparatus for collecting and extracting gaseous fumes emanating from the melting chamber of a tiltable furnace; and

FIGS. 2 and 3 are reduced side and rear elevational views of the apparatus, respectively.

DETAILED DESCRIPTION

FIG. 1 illustrates a furnace of the basic electric type, particularly adapted for making iron and steel. The furnace comprises a vessel 10 having a melting chamber 11 defined therein which may be suitably lined with a basic refractory and heated by graphite electrodes or the like (not shown). The chamber terminates at its upper end at an opening 12 which may be charged with selected scrap and pig iron for the production of deoxidized carbon and alloy steels which are thereafter tapped, killed and teemed into ingot molds in a conventional manner.

The vessel is pivotally mounted on a partially illustrated stationary support 13 by pivot means comprising a pair of laterally spaced and axially aligned trunnions 14, secured to the vessel. The horizontally disposed support is secured to a floor 15 of a foundry and is constructed to permit tilting of the vessel about axis A of the trunnions and to its phantom-line position illustrated in FIG. 2. Upon such tilting, molten metal is dispensed from a pour spout 16, formed integrally on a front side of the vessel.

The vessel has a laterally extending charging deck 17 secured thereto, in substantial horizontal alignment with support 13, which pivotally mounts a cover 18 thereon. The cover is pivotally mounted on an upstanding support 19, secured to the deck, for pivotal movements about a vertically disposed axis B. The cover is adapted to be pivoted by a suitable drive mechanism (not shown) disposed in support 19 to selectively cover opening 12. Such a covering position is illustrated in FIG. 3 wherein an annular clearance 20 of limited height is defined between the underside of the cover and the top side of a collector 21 for purposes hereinafter explained.

The collector comprises upper and lower parallel plates 22 secured together about a substantial portion of their perimeters by a vertically disposed outer wall 23. The vertically spaced plates and vertically disposed wall define a generally annular collecting means or chamber 24 which circumvents opening 12 to chamber 11. A plurality of upstanding and annular flow guide means or spacers 25 are secured between annular portions 26 of plates 22 which define a circular charging opening 27 therethrough to expose chamber 11. The cylindrical spacers are circumferentially disposed about the opening to define a restricted flow passage 28 between each adjacent pair of spacers.

Plates 22 and wall 23 are interrupted at an opening 29 formed through their front sides to permit pour spout 16 to project therethrough. Annular portions 26 of the plates are preferably detachably mounted thereon. Such portions, preferably composed of a highly heat resistant material such as stainless steel, may be removed to facilitate servicing of the spacers connected thereto.

A manifold 30 is secured to lower plate 22 and terminates at an upwardly facing inlet opening 31 which communicates with collecting chamber 24. Conduit means 32 communicate with the collecting chamber, via an outlet of the manifold, to conduct fumes exteriorly of the apparatus for scavenging purposes. The conduit means comprises a first conduit or duct 33 having its upper end pivotally mounted at 34 on manifold 30 for pivotal movement about a horizontally disposed axis C spaced laterally from axis A.

The lower end of the first conduit means is pivotally mounted at 35 on an end of a stationary second conduit or duct 36 for pivotal movement about a horizontally disposed axis D, parallel to axis C. The first conduit may comprise a first section 37 having a second section 38 slidably mounted therein to provide means for permitting the first conduit to continuously maintain communication with manifold 30 and thus collection chamber 24 upon tilting of vessel 10 and collector 21. The tolerances defined between the two telescopic sections are suitably sized to provide a static seal therebetween due to the relatively high velocity of the exiting gases.

Second conduit 36 has a conventional damper means, schematically illustrated at 39, operatively mounted therein to selectively control the cross sectional area of its flow passage. A suction fan means, schematically illustrated at 40 and positioned downstream of the damper means, functions to draw the fumes through the conduit means and into a scavenging system (not shown).

In operation, a factory crane or the like initially positions a charging bucket over opening 27 of the collector to charge chamber 11 with suitably composed scrap and pig iron. During such a charging phase of the foundry operation, damper 39 is actuated to fully open the flow passage of second conduit 36 to permit maximum fume extraction from melting chamber 11. Spacers 25 may be selectively spaced circumferentially to in turn vary the size of passages 28 relative to each other. Such variance will permit the integrated flow passages in collecting chamber 24, manifold 30 and conduit means 32 to be suitably sized and otherwise constructed to provide substantially uniform and nonturbulent flow (minimal frictional drag and pressure drops) therethrough upon extraction of the fumes during all phases of the foundry operation.

Cover 18 is then pivoted over opening 27 and the contents of vessel 10 are heated to their proper melt temperature. Simultaneously therewith, damper 39 is actuated to restrict the size of the flow passage in second conduit means 36 to conserve heat in the vessel. It should be noted, however, that a limited volume of ambient air is permitted to flow into the vessel and collecting chamber through annular clearance 20 (FIG. 3) and pour spout 16.

During the pouring phase of operation, cover 18 is maintained over opening 27 and damper 39 is actuated to its fully open position to insure maximum flow of the fumes through the conduit means. As shown by the phantom line illustrations in FIG. 2, a hydraulic actuator 41, pivotally mounted between the floor 15 and the deck 17 secured to the vessel 10, is then extended to simultaneously tilt vessel 10, cover 18, and collector 21 on trunnions 14 to dispense the melt through pour spout 16 and into suitably positioned ingot molds (not shown). During such tilting, sections 37 and 38 of the first conduit will telescope within each other, as further illustrated by phantom lines in FIG. 2.

Alternative means may be employed for maintaining the first conduit in continuous communication with the manifold and collecting means upon tilting of the vessel. For example, first conduit means 33 could be reconstructed as a one-piece duct. Such reconstruction would require a repositioning of manifold 30 and pivotal connection 34 to place axes A and C in coincident relationship relative to each other. Thus, the unitary first conduit would remain in its original position upon tilting of the vessel and manifold. In addition, pivotal connection 35 would not be required between the first and second conduit means. In addition, a second conduit means 32 and attendant hardware could be operatively connected to the collector on the opposite side thereof or at any other suitable location therearound.

What is claimed is:

1. An apparatus comprising a vessel defining a melting chamber therein which terminates at an opening at its upper end,

5 a horizontally disposed collector mounted on said vessel including a pair of vertically spaced plates each having an annular portion detachably mounted thereon and an opening formed through each of said annular portions communicating with the opening to said chamber,

10 pivot means pivotally mounting said vessel and said collector on said support,

generally annular collecting means defined in said collector to at least substantially circumvent the opening formed therethrough,

15 conduit means communicating with said collecting means for conducting fumes exteriorly of said collector comprising a first conduit pivotally mounted on said collector and communicating with said collecting means and a stationary second conduit connected directly to said first conduit and communicating therewith, and

20 means, including the pivotal mount of said first conduit on said collector, for maintaining said first conduit in continuous communication with said collecting means and said second conduit upon pivoting of said vessel and said collector.

2. The apparatus of claim 1 further comprising a horizontally disposed cover movably mounted on said collector to selectively cover the opening formed therethrough.

25 3. The apparatus of claim 1 wherein said pair of vertically spaced and horizontally disposed plates are secured together about a substantial portion of their perimeters by an upstanding sidewall to define said collecting means.

30 4. The apparatus of claim 3 further comprising a plurality of flow guide means secured between said plates and circumferentially disposed about the opening formed through said collector means to define a flow passage communicating said chamber with said collecting means between each adjacent pair of flow guide means.

40 5. The apparatus of claim 4 wherein said flow guide means each comprises a cylindrical spacer.

6. The apparatus of claim 4 wherein each of said flow guide means are attached between said annular portions.

45 7. The apparatus of claim 1 further comprising a manifold secured on said collector and having an inlet communicating with said collecting means and an outlet communicating with said first conduit.

50 8. The apparatus of claim 1 wherein the pivot axis for said pivot means is spaced laterally from the pivot axis at the pivotal mounting of said first conduit on said collector.

55 9. The apparatus of claim 1 wherein said means for maintaining said first conduit in continuous communication with said collecting means and with said second conduit further comprises a telescopic connection between first and second sections of said first conduit and a pivotal connection between said first and second conduits.

60 10. The apparatus of claim 1 further comprising damper means operatively mounted in a flow passage of said second conduit for selectively controlling the cross sectional area of said flow passage.

65 11. The apparatus of claim 10 further comprising suction fan means positioned downstream of said damper means in said flow passage.

12. An apparatus comprising

a vessel defining a melting chamber therein which terminates at an opening at its upper end, a horizontally disposed collector including a pair of vertically spaced plates mounted on said vessel, an annular portion detachably mounted on each of said plates, means forming an opening formed through each of said annular portions communicating with the opening to said chamber, and generally annular collecting means defined in said collector to at least substantially circumvent the opening formed through said annular portions.

13. The apparatus of claim 12 further comprising a plurality of flow guide means secured between said annular portions in circumferentially disposed relationship therearound to define a flow passage between each adjacent pair of flow guide means communicating said chamber with said collecting means.

14. The apparatus of claim 12 further comprising a horizontally disposed cover movably mounted on said collector to selectively cover the opening formed there-through.

15. The apparatus of claim 12 wherein said collector

comprises a pair of vertically spaced and horizontally disposed plates secured together about a substantial portion of their perimeters by an upstanding sidewall to define said collecting means.

16. The apparatus of claim 13 wherein said flow guide means each comprises a cylindrical spacer.

17. The apparatus of claim 12 further comprising conduit means communicating with said collecting means for conducting fumes exteriorly of said collector.

18. The apparatus of claim 17 further comprising a manifold secured on said collector and having an inlet communicating with said collecting means and an outlet communicating with said conduit means.

19. The apparatus of claim 17 further comprising damper means operatively mounted in a flow passage of said conduit means for selectively controlling the cross sectional area of said flow passage.

20. The apparatus of claim 19 further comprising suction fan means positioned downstream of said damper means in said flow passage.
